CLAIM

(21) Appl. No.: **29/241,604**

I claim the ornamental design for a device for connecting a tow bar to a vehicle to be towed, as shown and described.

(22) Filed: **Oct. 31, 2005**

DESCRIPTION

(51) **LOC (8) Cl.** 12-16

FIG. 1 is a perspective view of a device for connecting a tow bar to a vehicle to be towed showing my new design;

(52) **U.S. Cl.** **D12/162**

FIG. 2 is a top plan view thereof, the bottom plan view being a mirror image thereof;

(58) **Field of Classification Search** D12/110,

D12/111, 114, 117, 159, 160, 161, 162, 400;
180/84, 258; 280/5.5, 5.501, 5.502, 5.503,
280/5.504, 5.505, 5.506, 673, 668, 124.161,
280/124.106, 124.155; 285/57, 145.5, 226,
285/299; 92/34-39; 188/266.6, 274, 285,
188/318; 267/64.17, 67, 68, 135, 136, 218,
267/220; D15/138

FIG. 3 is a side elevational view thereof;

FIG. 4 is an elevational view of the opposing side thereof;

FIG. 5 is an end elevational view thereof;

FIG. 6 is an elevational view of the opposing end thereof,
and,

FIG. 7 is a reduced top plan view showing the invention in
use; the broken lines depict another device which is the
mirror image of the device for connecting a tow bar to a
vehicle to be towed and which is used in conjunction
therewith; the remaining lines depict environmental
structure for illustrative purposes only and form no part of
the claimed design.

See application file for complete search history.
